(57) **CLAIM**

The ornamental design for clog shoe, as shown and described.

DESCRIPTION

FIG. 1 is a perspective view of a clog shoe in accordance with a first embodiment of the present invention;

FIG. 2 is a front elevational view of the clog shoe of FIG. 1;

FIG. 3 is a rear elevational view of the clog shoe of FIG. 1; FIG. 4 is a left side elevational view of the clog shoe of FIG. 1;

FIG. 5 is a right side elevational of the clog shoe of FIG. 1; FIG. 6 is a top plan view of the clog shoe of FIG. 1;

FIG. 7 is a perspective view of a clog shoe in accordance with a second embodiment of the present invention;

FIG. 8 is a front elevational view of the clog shoe of FIG. 7;

FIG. 9 is a rear elevational view of the clog shoe of FIG. 7; FIG. 10 is a left side elevational view of the clog shoe of FIG. 7;

FIG. 11 is a right side elevational of the clog shoe of FIG. 7; and,

FIG. 12 is a top plan view of the clog shoe of FIG. 7.

The features presented in broken line format, including the outsole, the lace, the lace pull and the lace locking mechanism, form no part of the claimed invention.
